UNITED STATES PATENT OFFICE.

ROBERT W. MURRAY, OF NEW LEXINGTON, OHIO.

PUMP VALVE.

Application filed March 10, 1920. Serial No. 364,778.

To all whom it may concern:

Be it known that ROBERT W. MURRAY, a citizen of the United States, residing at New Lexington, in the county of Perry and State 5 of Ohio, has invented certain new and useful Improvements in Pump Valves, of which the following is a specification.

This invention relates to pumps and has particular reference to pumps of the type 10 wherein the fluid conduits thereof are formed from wood in order to be capable of withstanding acids or alkaline solution in order that the pumps may be employed in handling such corrosive fluids that can 15 not be successfully carried for any appreciable length of time by metallic structures.

Specifically, the present invention constitutes an improvement on the valve construction of such wooden pumps by providing 20 a valve structure of simple, durable formation and one wherein the position of the valve parts may be firmly maintained during operation and yet readily removable for purposes of adjustment and repair.

Another object of the invention resides in 25 improving the valve construction disclosed in my prior Patent No. 1,224,200 dated May 1, 1917 by amplifying its general formation and in providing means for preventing fluid 30 seepage through the removable cover members thereof.

With these and other objects in view, as will appear as the description proceeds, the invention accordingly consists in the novel 35 features of construction, combinations of elements and arrangement of parts, herein-after to be fully described and to have the scope thereof pointed out in the appended claim.

40 In the accompanying drawing, forming a part of this specification, and in which similar characters of reference denote like and corresponding parts:

The figure is a vertical longitudinal section 45 view taken through the pump wherein is embodied my improved valve construction.

As stated, the body of the pump is formed 50 of wood and consists essentially of a pair of vertically arranged blocks 1 and 2. These blocks are arranged so as to rest one on top of the other, and a gasket 3 is interposed between the adjacent surfaces of said blocks in order to render the joint therebetween

leak proof. Any suitable means may be provided for retaining the blocks in assembled relationship. The block 1 is longitudinally bored as at 4 to provide opposed piston chambers 5, in which wooden plungers may 55 slidably operate, said chambers being separated by means of transverse filler blocks 6 which are positioned centrally in such manner as to obstruct the bore 4. Communicating with the chamber 5 at the inner ends of the latter are vertically arranged bores 7 60 which pass vertically through the blocks 1 and 2.

Situated within the lower portions of the bores 7 are tubular liners 8, whose lower edges rest upon the longitudinal liners 9 positioned within the bores 4. The upper portions of the bores 7 within the block 1 are arranged to receive wooden valve seats 10, which latter are of annular formation and are so shaped as to be capable of being securely clamped between the meeting portions of the blocks 1 and 2. These seats are provided with a plurality of vertically arranged openings 11 which are normally closed by means of flat disk valves 12 of 70 rubber or other suitable material. Further, the bores 7 are provided with valve controlled ports 13 through which fluid may be drawn into the chambers 5. It will be understood that the plungers within said chambers operate in opposition to each other so that upon the advance stroke of the piston on one side to expel fluid from the pump the plunger on the opposite side will be moved 75 to draw a fluid into its chamber. This opposed arrangement is well known and provides for a double acting pump and hence permits of a continuous outflow of fluid.

After passing through the openings 11 and around the valves 12 the discharge fluid will 80 be directed into an intervening conduit 14 located between the bores 7 and above the valves 12. A discharge duct 15 leads from the conduit 14 and permits of a discharge 85 fluid from the pump. It will be manifest 90 that by virtue of this construction an entirely wooden pump is provided which will be free from the detrimental effects of fluids containing acids or the like, and hence the pump may be used in such particular capacities and under such conditions that metallic pumps similarly used would very soon fail 95 and become inoperative by the corrosive ac-

tion of the acids. The construction so far described is substantially the same as that set forth in my aforesaid patent and therefore is not specifically claimed hereinafter.

- 5 The present invention deals particularly with an improved valve construction for pumps of the character specified, and aims to provide a structure which will be simple and positive in operation, will be readily
- 10 removable and accessible and yet so constructed as to prevent an undue escape of fluid of joints defining the valve structure. To this end, the valves 12 are provided with axial openings 16, which are arranged to
- 15 slidably receive the reduced shank portions 17 of a pair of slidable valve stems 18. The body portions of the stems 18 are offset from the shank portions 17 in order to provide bearing surfaces 19, and springs 20 of any
- 20 suitable type are arranged between these surfaces 19 and the corresponding upper surfaces of the valves 12, said springs serving in the capacity of cushions to retard the upward movement of the valves 12. The
- 25 upper ends of the bores 7 are reduced and countersunk as at 21 to removably receive a plurality of head plates 22, which latter are formed with annularly offset rims 23 arranged to be received within the counter-
- 30 sunk portions 21 and to thereby retain the head plates in supported relationship with respect to the bores 7. The plates 22 are further formed to embody annular body portions 24, which are located normally
- 35 within the upper reduced ends of the bores 7. These portions 24 have their under faces formed with axially located sockets 25 in which are mounted the reduced ends 26 of a pair of guide bushings 27. These bushings
- 40 are, in turn equipped with vertical pockets 28 in which are slidably received the upper reduced ends of the stems 18. It will be noted that the pockets 28 are of sufficient depth to permit the valves 12 to close by
- 45 gravity and also to be slidably opened when responding to fluid pressure created within the chambers 5, the springs 20 being provided to arrest undue upward movement on the part of the valves and to gradually
- 50 check their upward movement. Upon release of the valves from the fluid pressure, the same will gravitate to a closed position. The parts so far described with the possible exception of the springs 20 are formed from
- 55 wood and hence are not open to the corrosive influence of the fluids which are designed to pass through the pump on their way to the outlet 15.

To effectively seal the upper ends of the bores 7 and yet to render the valve construction readily accessible, the upper surface of the block 2 is provided with a plurality of grooved metallic guides 29, which have their grooved faces located on opposite

65 sides of the bores 7. Arranged to be re-

ceived within the grooves of the guides 29 is a pair of cap plates 30 which are adapted to be positioned in axial registration with the bores 7. These plates 30 are provided centrally with threaded openings 31 in which are 70 adjustably positioned a plurality of set screws or their equivalents 32. The lower ends of these screws are adapted to frictionally engage with a pair of metallic wear plates 33 situated upon the upper surfaces of the head 75 plates 22. By virtue of this construction it will be manifest that by tightening the screws 32 into engagement with the wear plates 33, the latter will be pressed downwardly upon the head plates 22, thereby 80 forcing the rims 23 of the latter into firmly seated engagement with the gaskets 34 carried by the countersunk portions 21 of the bores 7. Manifestly, by means of this construction seepage of fluid from the joints 85 defined by the valve structure will be effectively prevented, and the operation of the pump thereby rendered reliable. To remove the valve parts, however, it is simply necessary to loosen one or both of the screws 32. 90 This permits of the convenient removal of the cap plates 30, and with these removed it follows that the internal parts of the valve structure may be likewise taken out of the bores 7 and suitably adjusted or repaired. 95 To prevent the wear plates 33 from losing their operative positions, the head plates 22 are provided with set screws or their equivalents 35, the heads of which are positioned within the sockets 25 and are maintained therein by the wedged bushings 27. This construction causes the shank ends of the screws 35 to project above the upper surfaces of the plates 22 so as to be received within small centering openings 36 provided 100 in the under faces of the wear plates. This construction retains the plates in operative positions and prevents their slipping upon the application of pressure thereto.

It will thus be manifest from the foregoing description that the present invention provides an efficient, durable and readily removable valve structure for wooden pumps, and one wherein all parts are conveniently accessible and yet fluid seepage 110 through the joints thereof will be prevented. Various changes in the form, preparation and the minor details of construction may be resorted to without departing from the spirit or sacrificing any of the advantages 115 of the invention.

What is claimed is:

In a pump of the class described, a wooden body having a fluid conducting bore formed therein, a valve seat located in the bore, a 125 disc valve engaged normally on the seat, a stem having a reduced shank for passage through the valve disc for sliding engagement with the seat, said stem having an annular offset overhanging the valve disc, a 130

spring encircling the shank and engaged with the offset and valve disc, a plate engaged with the body and having a bushing mounted therein, said bushing having a

5 pocket formed therein for slidably receiving the upper end of the valve stem, a cap plate removably mounted on the body, a wear

plate interposed between the first named plate and cap plate, set screws carried by the cap plate and first named plate and engaged, respectively, with the wear plate. 10

In testimony whereof I affix my signature.

ROBERT W. MURRAY.
